CLAIM

The ornamental design for a display screen with progress bar for recorded video, as shown and described.

DESCRIPTION

FIG. 1 is a front view of a display screen with progress bar for recorded video showing my new design;

FIG. 2 is a front view of another embodiment of a display screen with progress bar for recorded video showing my new design;

FIG. 3 is a front view of another embodiment of a display screen with progress bar for recorded video showing my new design;

FIG. 4 is a front view of another embodiment of a display screen with progress bar for recorded video showing my new design;

FIG. 5 is a front view of another embodiment of a display screen with progress bar for recorded video showing my new design;

FIG. 6 is a front view of another embodiment of a display screen with progress bar for recorded video showing my new design; and,

FIG. 7 is a front view of another embodiment of a display screen with progress bar for recorded video showing my new design.

The broken line showing of the display screen is included for the purpose of illustrating unclaimed environment and forms no part of the claimed design.
